UNITED STATES PATENT OFFICE.

GEORGE W. NIEDRINGHAUS AND CHRISTIAN GEISS, OF ST. LOUIS, MISSOURI,
ASSIGNORS TO THE ST. LOUIS STAMPING COMPANY, OF SAME PLACE.

HINGE.

SPECIFICATION forming part of Letters Patent No. 449,628, dated March 31, 1891.

Application filed December 20, 1890. Serial No. 375,289. (No model.)

To all whom it may concern:

Be it known that we, GEORGE W. NIEDRINGHAUS and CHRISTIAN GEISS, residents of St. Louis, Missouri, have jointly made a new and useful Improvement in Hinges, of which the following is a full, clear, and exact description.

The improvement relates more especially, but not exclusively, to hinges used in attaching the lids of coffee-pots, tea-pots, and other vessels of sheet-metal ware; and it consists in the special mode of constructing and connecting the hinge with the body or handle of the vessel, substantially as is herein-after described and claimed, aided by the annexed drawings, making part of this specification, in which—

Figure 1 is a view in side elevation showing detached from each other the parts of the improved hinge; Fig. 2, a view in perspective of the hinge parts assembled; Fig. 3, a side elevation, partly in section, of a vessel having the improved hinge, only that portion of the vessel which is needed for an understanding of the improvement being exhibited; Fig. 4, a section on the line 4 4 of Fig. 3, and Fig. 5 a top view of that part of the construction in the immediate vicinity of the hinge.

The same letters of reference denote the same parts.

The vessel A is of any of the usual descriptions of sheet-metal vessels, saving as it may be modified or supplemented by the improvement under consideration.

B represents the vessel-body; C, the handle, and D the lid. Each and all of these parts may be varied in construction so long as they are adapted to receive the hinge, which is represented at E.

The hinge is composed of three parts, substantially—a piece e of sheet metal and two pieces e' e' of wire. The sheet-metal piece e is folded to form the leaves e² e², and at the line of folding e³ it is opened to receive the ends e⁴ e⁴ of the wires e' e', respectively. The wires are bent, substantially as shown, to form the ends e⁴ e⁴, the middle portions e⁵ e⁵, and the ends e⁶ e⁶. The portions e⁵ e⁵ are substantially parallel with the ends e⁴ e⁴, and the ends e⁶ e⁶ project at right angles, or thereabout, from the portions e⁵ e⁵, and at the extremity e⁷ thereof are enlarged to form shoulders thereon.

The handle C, which is conveniently made of sheet metal, with its side portions c c folded underneath the main portion c', and so as to make the sides c² c² somewhat thicker than the central portion c³ of the handle, is perforated at c⁴ to receive the ends e⁶ e⁶ of the wires e' e'—that is, the wires having their ends e⁴ e⁴ inserted in the enlargement e³ of the folded part e are secured to the handle by passing the ends e⁶ e⁶ through the perforation c⁴, so that said ends shall project through and beyond the perforation, and then locking the same in the perforation by applying solder F to and around said projecting ends, so as to become interlocked therewith and to spread around the perforation at the under side of the handle, and thus form a head upon the combined ends e⁶ e⁶ to fasten them in the handle, substantially as shown in Figs. 3 and 4. The recess in the inner side of the handle, due to the sides being thicker than the central portion of the handle, as described, affords room for the described head upon the ends e⁶ e⁶, and the sides c² c² respectively support said head at the sides thereof. The other part—namely, the piece e—of the hinge is connected with the lid by inserting the lid-flange d between the leaves e² e² and soldering the parts together or otherwise uniting them, substantially as shown.

The two wire parts e' e' might be in the form of a single part, as shown in Fig. 4, which exhibits this modification of the construction, and any equivalent means may be substituted for the solder F in forming the head upon the ends e⁶ e⁶.

I claim—

The combination of the handle, lid, hinge, and solder, said handle being recessed and perforated, as described, and said hinge having the folded part e and wires e' e' shaped to form the ends e⁴ e⁴, the middle portions e⁵ e⁵, and the shouldered ends e⁶ e⁶, substantially as described.

Witness our hands this 12th day of December, 1890.

GEORGE W. NIEDRINGHAUS.
CHRISTIAN GEISS.
